WOMEN'S JEAN

George M. Hattori, Denver, Colo., assignor to
The Prior Co., Denver, Colo.

Term of patent 14 years

Filed Sept. 9, 1974, Ser. No. 504,513

Int. Cl. D2—02

U.S. Cl. D2—28

FIG. 1

FIG. 3

FIG. 1 is a rear elevational view of a women's jean showing my new design;

FIG. 2 is a front elevational view; and,

FIG. 3 is a right side elevational view, the left side being a mirror image thereof.

I claim:

The ornamental design for a women's jean, as shown and described.
